SERVICE STATION WATER AND AIR
DISPENSING COLUMN

Earnest E. Martin, Pasadena, Calif., assignor, by
mesne assignments, to John Wood Manufacturing Company, Inc., New York, N. Y., a corporation of Delaware

Application June 18, 1948, Serial No. 147,043

Term of patent 14 years

(Cl. D52—2)

To all whom it may concern:

Be it known that I, Earnest E. Martin, a citizen of the United States, residing at Pasadena, State of California, have invented a new, original, and ornamental Design for a Service Station Water and Air Dispensing Column, of which the following is a specification, reference being had to the accompanying drawing, forming a part thereof.

The drawing figure is a perspective view of a service station water and air dispensing column, showing my new design.

The portions of the water and air dispensing column not disclosed are substantially plain in appearance.

I claim:

The ornamental design for a service station

water and air dispensing column, substantially as shown and described.

EARNEST E. MARTIN.
